UNITED STATES PATENT OFFICE.

HOLGER VARDER, OF NEW YORK, N. Y.

CAR BUMPER.

Application filed February 12, 1927. Serial No. 187,682.

This invention relates to car-bumpers for railway sidings and track ends.

The object of the invention is to provide an efficient bumper especially to be associated with a bumping-post and which is simple and compact in design and construction and at the same time strong and capable of offering a great resistance in use.

These and other objects hereinafter set forth are attained by the means illustrated in the accompanying drawing, in which

Fig. 1, is a side elevation of the improved bumping post.

Fig. 2, is a central longitudinal vertical section through the casing and showing the movable parts in side elevation, and

Fig. 3, is a horizontal section on the line 3—3 of Fig. 2, and showing the movable members in plan.

Figures 4 and 5 are detail perspective views of different forms of friction blocks.

Similar reference numerals in all of the figures of the drawings designate like parts.

Referring to the drawing the numeral 10 designates the bumping-post proper which is mounted in a vertical position at the end of a railroad track 11 whose terminal ends are bent upwardly and suitably connected to a metal backing member or brace 12 of the usual construction.

On the front face of the post 10 is mounted a metal casing 13, the same being provided with a back-wall 14, a top-wall 15 and side-walls 16, and is rigidly secured in place upon the post by suitable bolts 17 which pass through the post and suitable ears on the backing-member 12 where they are held by nuts 18 threaded thereon. This casing 13 is formed with an open bottom side, for a purpose hereinafter set forth, and is provided with flanges 19 at the front end thereof for strengthening the same. It is also formed with a boss or rib 20 on the underside of its top-wall 15 and which is apertured to receive a strain-bolt 21, the boss or rib serving as a reinforcement for the top wall at this point.

Mounted upon the strain-bolt 21 within the casing 13 is a friction block 22 provided with a vertical face at its rear side adapted to frictionally engage an inner vertical face of the rear wall 14, and is also provided with an inclined face 23 at its front side which serves as a friction face and is adapted to be frictionally engaged by an inclined face 24 formed at the rear side of an operating

wedge 25 which extends forwardly beyond the front mouth of the casing 13 and has secured to its front face a suitable striking-block 26, said striking-block being formed wider than its wedge so that its ends will project beyond the sides thereof. This wedge 25 is also mounted upon the bolt 21 and is provided with a slot 27 through which the bolt 21 extends, the slot permitting a limited movement of the wedge 25 backwardly and forwardly in the casing and on the bolt.

Friction-block 22 is supported in position within the casing by a buffer-spring 28 which is mounted around the vertically positioned strain-bolt and at one end engages the underside of the block 22, and at its other end is engaged by a disk 29 which supports the spring and said disk is in turn suitably supported by the nuts 30 that are threaded upon the lower end of the strain-bolt, the nuts being adapted to be adjusted upon the bolt to regulate the tension of the spring and thus regulate the amount of resistance to be offered by the wedge-shaped friction-block 22.

The boss or rib 20 as formed, not only serves to reinforce the top wall where the bolt passes through, but also serves to concentrate the upper pressure near the center of the top wall of the casing and closely adjacent to the strain-bolt.

In operation, assuming the parts to be in the position shown in Fig. 2, when a train 90 engages the striking-block 26 the wedge 25 will be forced backwardly and consequently the block 22 will be forced downwardly against the resistance of the spring 28. During the movement of the blocks 25 and 22 friction will be had upon the surfaces of the rear-wall, the boss or rib 20 and also between the inclined faces of the blocks and these frictional resistances together with that of the spring 28 will serve to take up 95 the concussion between the train and the post. When the pressure is relieved against the buffer, the spring will automatically return the parts to normal position.

It will be understood that instead of using 105 a single friction block 22, a double block 22' may be used as shown in Figure 5.

Having thus fully described the invention, what is claimed is:—

1. A car bumper comprising a casing open 110 at one end and adapted to be secured to a bumping-post, a strain-bolt passing verti-

10 cally through the casing and supported by the top-wall thereof, a resistance spring mounted around the lower end of strain-bolt, a vertically movable friction-block supported by said resistance spring and provided with a rear face for frictionally engaging the rear wall of the casing and an upwardly and rearwardly inclined front face, and an operating-wedge projecting through the open end of the casing with its top surface in engagement with the top wall thereof and provided with an inclined rear face in frictional contact with the inclined face of the vertically movable friction-block.

15 2. A car bumper comprising a casing having open front and bottom sides and adapted to be secured to a bumping-post, a strain-bolt passing vertically through the casing and supported by the top wall thereof, a resistance spring mounted around the lower end of the strain-bolt, a vertically movable friction-block supported by said resistance spring and to move through said open bottom side of the casing and provided with a rear-face for frictionally engaging the rear wall of the casing and also having an upwardly and rearwardly inclined front face,

30 and an operating wedge projecting through the open end of the casing with its top surface in engagement with the top wall thereof and provided with an inclined rear face in frictional contact with the inclined face of the vertically movable friction-block.

35 3. A car bumper comprising a casing open at its front end and adapted to be secured to a bumping-post, a strain-bolt passing vertically through the casing and supported by the top wall thereof, said casing being provided with an interior boss or rib on its top wall at a point where the strain-bolt is supported, front and rear wedge-blocks mounted within the casing, said front wedge-block constructed to frictionally engage said boss and rib to concentrate the upper pressure upon the top wall adjacent to the strain-bolt, and also constructed to frictionally engage a face of the rear friction-block to move it downwardly under pressure, and a resistance spring mounted upon the strain-bolt below the rear friction-block and in engagement therewith to support the same.

40 45 In testimony whereof I affix my signature.

50 HOLGER VARDER.
